G. RITTER

FLEXIBLE SHINGLE

Filed Sept. 3, 1925

FIG. I.

FIG. II.

WITNESSES

Thomas W. Kerr, Jr.
Frederick A. Kraus

INVENTOR:

George Ritter,
Frank O'Dowd,
ATTORNEYS.

UNITED STATES PATENT OFFICE.

GEORGE RITTER, OF WOODBRIDGE, NEW JERSEY, ASSIGNOR TO THE BARBER ASPHALT COMPANY, OF PHILADELPHIA, PENNSYLVANIA, A CORPORATION OF WEST VIRGINIA.

FLEXIBLE SHINGLE.

Application filed September 8, 1925. Serial No. 54,188.

This invention relates generally to weather-proof surface coverings, while it has more particular reference to shingles fabricated from sheet material of a fibrous nature and 5 treated with bituminous substance to impart weather resistant qualities, such shingles being usually finished on one or both faces with a mineralized surfacing imbedded or rolled therein.

10 An object of this invention is to provide shingles, of the type referred to which, when laid in overlapping relation, simulate the conventional rectangular units, but by reason of their novel shape effect a considerable 15 saving in material per "square" covered therewith.

Another object of the invention is to provide a surface covering for roofs and the like that affords ample weather protection 20 while considerably reducing the weight of material laid.

A further object is to provide flexible shingles of the type referred to characterized by means for spacing and aligning the 25 same during the laying process, so that it is not necessary for the roofer to previously chalk line a surface to be covered with the novel shingles.

With the foregoing and other objects in 30 view, which will be apparent from the following description, this invention essentially consists in the form of shingle herein-after described, typically exemplified on the accompanying sheet of drawings, and circumscribed as to subject-matter and scope 35 by the appended claims.

In the drawings:—

Fig. I is a plan view of a shingle embodying the present improvements, and showing 40 by dot-and-dash lines how it is economically severed from web material; and,

Fig. II is a fragmentary plan view of a surface, in part, covered with my novel type of shingles.

45 In accordance with this invention I preferably make use of sheet material rendered flexible, non-porous and weather-proof in accordance with known practice in the art to which said invention appertains. This 50 material is, in general, made of standard widths and I preferably use that having a transverse dimension equal to the depth of shingles it is desired to produce. As shown in Fig. I, such a strip of sheet material is

designated 3, by dot-and-dash outline, and 55 it is transversely severed by zig-zag cross-cuts to provide the individual shingle units 4. It will be remarked the consecutive units are cut from the strip of sheet material 3 in 60 reverse relation, while each individual shingle 4 embodies upper and lower rectangular portions 5, 6 respectively with an integral intervening polygonal or mutually merging trapeziform section 7. More specifically set forth, the upper portion 5 is square, the 65 lower portion 6 oblong, while the integral intermediate section joins up to said square portion 5 with provision of indents or notches 8 and it is formed adjoining the oblong portion 6 with laterally projecting lugs 70 9, 9 for a purpose later on explained. Attention is also, particularly, directed to the fact that the side edges 10 of the portion 5, 75 the similar edges 11 of the portion 6 and the edges of the lugs 9, are all in parallel or directly vertical to the upper and lower edges 12, 13—respectively—of the shingle 4. It is, likewise, to be noted that the depth of the upper and lower portions 5, 6 are equal, 80 while the width of the former is slightly in excess of half the greater dimension of the latter, and that the shingles 4 are cut from roll roofing material with minimum waste, and a marked saving of time and labor.

Shingles 4 of the typified character are 85 laid as follows:—

A starting strip 14 is first attached to the roof or other boarding 15, in any of the well known ways, whereupon the first or lower row of shingles 4 are secured by nails 90 16 located adjacent the lugs 9 aforesaid; or otherwise—in the accustomed manner—as far as may be necessary to properly retain the same in position and alignment with the longitudinal edge of the starting strip 14. 95 Successive overlapping rows of the shingles 4 are similarly laid and nailed, in staggered relation, one to the other in accordance with general practice. It will thus be seen that the individual shingles 4 are secured to the 100 boarding 15 at four points, the lug projections 9 ensuring the proper horizontal spacings 17 as well as an efficient weather seal at 18, whereas the angular points *a*, *b*, *c*, 105 register with one another in the vertical spacing and thereby regularly square the work, all of which will be easily appreciated on an examination of Fig. II. Further-

more the relative amount of exposure of each individual shingle will be clearly seen and understood by those acquainted with the art, while the saving in material used—and 5 less weight applied—is equally obvious.

From the foregoing it will be apparent that my novel form of shingle fully justifies all the objects and advantages set out in the hereinbefore recited statement of invention. 10 Furthermore, while it is deemed preferable to employ the embodiment illustrated and described, it will be understood the same may be varied or modified as found desirable and best suited to individual requirements.

15 Having thus described my invention, I claim:—

1. As a new article of manufacture a flexible shingle configured to afford upper and lower rectangular portions in parallel and 20 of contrasting area, with a mutually merging intermediate trapeziform section having lateral lugs and opposed notches providing relatively-stepped rectangular points for the purposes set forth.

2. As a new article of manufacture a flexible shingle configured to afford upper and lower rectangular portions in parallel and of minor and major area respectively with a 25 mutually merging intermediate trapeziform section, said intermediate section having opposed lateral lugs and notches, the former functional to provide the usual spacings and the latter affording relatively-stepped vertical-aligning angle points.

3. A weather-proof surface covering composed of a series of overlapping rows of flexible material shingle units each embodying an upper and a lower rectangular portion—of contrasting area—with a mutually merging intermediate trapeziform section, 35 said intermediate section including opposed flanking lugs and opposed notches whereby horizontal spacing and vertical aligning are positively ensured.

In testimony whereof, I have hereunto 40 signed my name at Maurer, N. J., this 14th day of August 1925.

GEORGE RITTER.
